[57] **CLAIM**

The ornamental design for a boat trailer bunk guide, as
shown and described.

DESCRIPTION

FIG. 1 is a top perspective view of a boat trailer bunk guide,
showing my new design;

FIG. 2 is a bottom perspective view thereof;

FIG. 3 is a front view thereof;

FIG. 4 is a side elevational view thereof;

FIG. 5 is a top plan view thereof; and,

FIG. 6 is a bottom plan view thereof.

The broken line portions of FIGS. 2 and 6 form no part of
the claimed design.
